MULTIPLYING MACHINES

Michael Maul, Schwabach, near Nurnberg, Germany

Application February 20, 1953, Serial No. 338,070

Claims priority, application Germany March 4, 1952

21 Claims. (Cl. 235—61.6)

This invention relates to multiplying machines and more particularly pertains to improvements therein resulting in a simplified, yet fully efficient and effective, machine.

In multiplying machines operating on the basis of the decimal system the simplest method of multiplication is that of repeated addition. In this method, the multiplicand is repeatedly added as many times as is indicated by the digit of a multiplier denomination. Such addition is repeated for all multiplier denominations under consideration of the necessary column shifting between multiplicand and product device. This method permits a very simple construction of the machine since in fact the machine acts essentially as an adding machine. However, a comparatively slow operating speed is inherent in such a system due to the numerous adding operations necessary.

In order to reduce the multiplying time, it has been proposed to use multiplication devices which immediately form partial products. In machines of this type, the digit of a decimal denomination of the multiplier is simultaneously multiplied by all decimal denominations of the multiplicand and the product thus obtained, usually referred to as a partial product, is entered into the product device. Thereafter, the same operation takes place for the next decimal denomination under consideration of the above mentioned column shifting between the product device accumulating all partial products and the multiplicand. The faster operation of this second mentioned method must, however, be purchased at the price of a more complicated construction, which chiefly is due to the multiplying device.

Further suggestions have already been made to compose the digit of the factors expressed in the decimal system according to a predetermined code in component values the additive sum of which corresponds to the respective digit, and to form so called sub-products by the multiplication of the component values. Thus, in each instance, all multiplicand denominations are multiplied by each component value of a multiplier denomination by means of a multiplying device. The machine according to this known suggestion needs, however, a special multiplying device for each sub-product and moreover the same device must be provided separately for each multiplicand denomination.

One object of the present invention is to provide a machine which operates faster than those according to the principle of the repeated addition, which, however, is of more simple construction than the machines according to the above mentioned second and third methods. This is obtained by means of a unitary sub-product device adapted to multiply any two components, represented in retaining means, by each other to form an individual sub-product, means being provided for controlling said sub-product device for the successive individual multiplication of each component of the multiplier digit by all components of the multiplicand digit through said sub-product device by entering different components thereinto, and sub-product accumulating means being provided in which

2

said sub-products are entered successively as they are formed. Thereupon in a manner known per se after multiplication of a multiplier denomination the column shifting between multiplicand and product device takes place in accordance with the successive multiplication by the various multiplier denominations.

As has been mentioned above, in the known suggestion working with sub-products, not only separate sub-product devices are used for each sub-product but these devices are also separately necessary for each denomination of the multiplicand. Accordingly, it is another object of the invention to provide means whereby the component multiplication device may not only be common to all sub-products but also to all decimal denominations of the multiplicand.

It is another object of the present invention to provide a multiplying machine which efficiently combines the advantages of the above mentioned known methods of multiplication and at the same time avoids their disadvantages. In any event, the invention permits an extraordinarily simple multiplying device.

Still another object of the instant invention resides in the selection of such component values, the highest sub-product of which does not become higher than 9. In this instance, a single accumulator device with the conventional tens transfer can be used in contrast to conventional devices in which products are formed being higher than 10 and which therefore require separate accumulators for entering of the units and tens values.

Preferably, each digit is represented by component values which may be formed by single components or by combinations of the components 1, 2, 3, 3. In this instance, all digits from 1 to 9 may be represented additively by the component values and the highest sub-product is not higher than 9. The sub-products are then 1, 2, 3, 4, 6 and 9. However, the component values 1, 2, 2, 2, 2 may also be chosen in which instance, however, a greater number of settings for the component values is required which is still smaller than the number of sub-products in the above mentioned component selection. Consequently, the less different component values are necessary to represent a digit, the less different sub-products are required to be represented by the multiplying device. In this way, the number of the operating cycles is, however, increasing and thereby more time is required for the multiplication.

The invention may be carried out in various manners. A preferred embodiment, as described in the following, possesses, however, a number of features which are emphasized in the specification and in the claims. One of the most essential features is the application of a specially constructed and controlled crank drive acting as a multiplying device.

For the scope of the invention, it is also immaterial how the entering of the factors and the manifestation of the product is effected. In the embodiment hereinafter described, the entering of the factors takes place under perforated record card control and the manifestation of the product by punching the controlling record card. The illustrated embodiment would therefore belong to the group of the punched card controlled so called "multiplying punches." The storing of the factors is therein effected in storing devices and product punching under the control of the product accumulator. It is, however, obvious that the perforated record card control may equally well be replaced by a key control or that the entering of the factors can be effected in any other way, and it is also evident that the manifestation of the product instead of being effected by punching is possibly carried out by printing or by any other conventional method.

A preferred embodiment of the invention is illustrated in the accompanying drawings:

Fig. 1 shows a perforated record card which for reasons of simplicity, is only punched in the middle deck with two factors and the product of the same.

General explanation

In the machine hereinafter described the two factors are taken off the one and the same deck of the card and the product is punched in this deck at the end of the multiplication. The factors are transferred from the card to storing devices from which the removal proper of the component values for the multiplication is effected. The products of the various multiplication operations are added one by one into an accumulator. The accumulator shows consequently at the end of all multiplication operations the complete product and is therefore designated as the product accumulator. When the multiplication is finished the product accumulator is analyzed and its setting is transferred to a punching device under which the card has been passed in the meantime; punching of the product is now effected in said card. With the punch-

ing of the card the following card is analyzed at the same time and the factors are entered into the storing devices from which then in turn the component values for the multiplication are derived.

5 A card which is used in the machine is illustrated in Fig. 1. The card consists of three decks each comprising 30 columns each of the columns having six hole positions. Punching in the card is effected by hole combinations as indicated by the code in Fig. 3. According to 10 this code the meaning of one hole combination is composed of the various component values associated with the various hole positions. These values are indicated in the column W while the column P indicates the positions (I—V). If for instance the first and third position is 15 punched the value is composed of the value 1 (position I) and of the value 3 (position III) which amounts to the value 4. In a similar manner the meaning of each of the numerals 0—9 will follow from the component values punched in the positions I to V. As shown in Fig. 3 20 five hole positions are used for the representation of the numerals. The division of the card according to Fig. 1 shows, however, six hole positions for the representation of letters which, however, is of no importance for the present invention.

In order to permit a simpler construction of the machine the two factors and the product are punched into the same deck of the card. It is herein of no importance in which deck the factors and the product are provided. The selection of the decks is possible by means of a simple 25 device in the plug board to which reference will be made in the description of the circuit diagram. Moreover it is immaterial in which column the factors and the product within one deck are provided; for it is possible to connect through a plug board each column with each storing device or product accumulator denomination.

The device for the analysis of the factor storage device is so constructed that the component values may be obtained again in the same manner as indicated according to the code in Fig. 3. But for the multiplication itself the 40 agreement is not absolutely necessary. For the multiplication there is only necessary a code which is suitable for the same whereas the factor perforation in the card may be effected according to any known code. This is possible since the combinations represented in the storing devices are effective only within the multiplication device 45 but are not transferred to the punching device. The setting of the punching device is rather effected through the product accumulator, the setting of which must thereafter represent the combinations in accordance with the code according to which the card has been punched. The 50 arrangement chosen for the described embodiment in which the code for the perforation of the card is the same as is used for the multiplication, has the advantage that the same crank drive may be used for the entering of the values into the storing devices as well as for the multiplication. The multiplication is effected in several 55 consecutive setting operations, whereby within each setting operation a component value of a multiplier digit is multiplied successively by all component values of a multiplicand digit.

60 At first all digits of the multiplicand are multiplied at the same time by the lowest digit of the multiplier and after each forming of the sub-product the sub-product is entered into the product accumulator. Subsequently displacement to the tens place of the multiplier and displacement of all multiplicand denominations with respect to the product accumulator by one denomination is effected, whereupon again multiplication of all multiplicand digits and entering of the sub-products into the accumulator is effected.

65 The multiplication by one digit of the multiplier is, however, not effected—as has been already indicated—in a single stroke but consecutively by the various component values of the multiplier digit. Thereby a complicated 70 sub-product device is avoided since only the various com-

ponent values are multiplied by each other. The same are selected in such manner that the highest product of the same is always smaller than 9. This affords the advantage that a simple accumulator device can be used as the product accumulator.

The performance of a calculation with the various component values may be seen from the example in Fig. 4. In this example 24 871 is to be multiplied by 7. The division of the numerals of the two factors—in accordance with the values W in Fig. 3—may also be seen in Fig. 4. In the first step the first component value of the numeral 7—namely 1—is multiplied simultaneously by the first component value—which is also 1—of each denomination of the number 24 871. The multiplication is, however, only effected in those denominations of the multiplicand having a significant figure, that is to say where there is no zero. Subsequently the second and thereafter the third and finally the fourth component values of the number 24 871 are multiplied by the first component value of the numeral 7. After all component values of the multiplicand have been multiplied by the first component value of the numeral 7 further displacement to the second component value of the numeral 7 takes place. But since this is zero the device will be immediately set to the third component value (namely the component value 3) and again all component values of the number 24 871 are multiplied successively. Subsequently the machine will be set to the fourth component value of the numeral 7 (again component value 3) and the same will be also multiplied by all component values of the number 24 871.

The translation for the setting of the storing device and for multiplying is preferably effected by means of a crank drive with two variables and by a continuously rotating crank. Three different embodiments are shown diagrammatically in Figs. 5 to 7. The crank drive has been chosen because it permits a safe clutching and uncoupling of the accumulator elements at the dead centers and because the return movement can be used for an automatic unclutching which will be referred later to below.

Fig. 5 shows diagrammatically a crank drive having a crank 11 with variable crank radius and with a variable rocking point of the pusher bar 12. The possibility of the variation has been illustrated diagrammatically in this picture by screwthreaded spindles. To the right hand end of the pusher bar 12 there is pivoted a pawl 13 acting upon a ratchet wheel 14 of the product accumulator. The stroke of the pawl may now be varied on the one hand by variation of the radius of the crank 11 and on the other hand by moving of the guide 15 and consequently of the rocking point. Accordingly also the ratchet wheel 14 will be displaced through more or fewer teeth. Depending on the setting of the crank 11 and the rocking point the latter being determined by the guide 15, a definitely determined stroke of the pawl will follow. If the setting of the rocking point and of the crank radius takes place in agreement with the component values of the factors the stroke of the pawl will result as a product of the two settings.

A further diagrammatic embodiment is illustrated in Fig. 6 which embodiment uses a crank 16 with constant radius and two pusher bars 17 and 18 which are arranged in series. The connection between the two pusher bars 17 and 18 is jointed. Each pusher bar has an own rocking point which is variable for itself. The rocking point may be varied by moving of the guides 19 and 20 and in similar manner as in the arrangement according to Fig. 5. A pawl is pivoted to the right hand end of the pusher bar 18, said pawl acting upon a ratchet wheel of the product accumulator in a similar manner as in Fig. 5. If the crank 16 is rotated the pusher bar 17 will rock about its rocking point. Depending on the position of the guide 19 its right hand end will carry out a larger or smaller movement. Due to the pivotal connection the left hand end of the bar 18 is forced to follow this rock-

ing movement whereby the bar 18 rocks about its pivot which is determined by the guide 20. Depending on the position of the guide 20 the rocking at the right hand end, to which the pawl is pivoted, is diminished or increased. The stroke of the pawl therefore depends on the position of the two guides 19 and 20. The positioning of the guides 19 and 20 is determined by the component values of the factors so that the stroke of the pawl will result as the product of the two settings.

If only a small number of component values is to be multiplied by each other, as is, for instance, the case in the machine hereinafter described in detail, in which, in fact only the numerals 1, 2 and 3 are multiplied by each other and by themselves, one of the variables of the crank drive may be replaced by different ratios of the gears. With the employment of the component values 1, 2 and 3 it is then possible to work with three translations. A diagram of a crank drive which operates according to this principle is shown in Fig. 7. The diagram corresponds to the practical embodiment as it is used in the machine described below, only the gear ratio has been illustrated somewhat differently in order to facilitate the explanation.

The arrangement in the machine is such that the storing devices of the factors as well as the product accumulator are driven by a single crank drive, the setting of which is effected cyclically with regard to the card analysis and to the multiplication operations respectively, and to which the various storing devices or accumulator elements are clutched for the time during which a transfer is effected to them. The guide setting is effected—in accordance with the component values—synchronously with the analysis of the card or with the analysis of the storing devices and of the product accumulator respectively.

The crank 21 is continuously driven with constant speed in counterclockwise direction. On the other hand upon each full revolution of the crank 21 the crank 22 is displaced one step in counterclockwise direction. This displacement will be described in more detail later on. A rod 24 is pivoted to the crank 21, said rod being provided for reciprocating movement in the guide 25. (This guide is only symbolically indicated in Fig. 7 while actually it is constructed differently therefrom). The right hand end of the rod 24 describes an ellipse-like curve. If the guide 25 is moved the curve will change. At the right hand end of the rod 24 there is a rocker 23 connected thereto by the link 26 which latter rocks in accordance with the curve. The angle through which the rocker 23 swings is dependent upon the shape of the curve. The guide 25 is now moved in such a way as to cause the various angles of swing of the rocker 23 to be proportioned to each other in the same manner as the component values I to IV in Fig. 3 (i. e. 1:2:3:3). In all four positions (the third position is identical with the fourth position) a constant angle must be subtracted in which the rocker runs idle on account of the play between the gears, and other parts. This play is also necessary for another reason as will be shown later, it is intentionally increased so that the drive can remain stationary at the moment of clutching.

The position and dimensions of the crank drive have been chosen in such a manner that at the lower dead centre of the rocker 23 the guide 25 as well as the auxiliary crank drive cooperating therewith (described later) may be adjusted without changing the position of the rocker 23. This is necessary since the clutch for the clutching of the storing device and accumulator places respectively to their drive must be always in the same position independently of the position in which the guide 25 happens to be. It is only necessary to take care that the guide 25 has already reached the positions (indicated in Fig. 7 by Roman numerals in accordance with the hole position designation according to Fig. 3) associated with the hole position at the upper dead centre of the rocker

23 (indicated in dash lines in Fig. 7) since the position of this point is a measure for the component value by which the storing device wheel and the product wheel respectively will be advanced.

The adjustment of the guide 25 is effected by the crank 22. Dimensions and position have been chosen here in such manner that the unequal distance between consecutive positions of the guide 25 on the rod 24 are transformed into equal movements of the crank 22. This is an advantage in so far as in addition to the step by step shifting also a continuous drive of the crank 22 can be derived from crank 21, if desired.

The rocker 23 is connected to the toothed segment 27 meshing with the toothed wheels 28 and 29. The ratio of the diameters of the segment and the two gears has been here so chosen that they have the same relation to each other as do the component values 3:2:1. The drive to the clutches for the accumulators may now be directly clutched to the segment or to one of the two gears 28 and 29. According to whether the clutching is to the toothed segment or to one of the two gears so is the respective translation effective upon the drive. Consequently the rocking movement of the rocker 23 is multiplied by the ratio of the gears. This arrangement permits a simplification of the crank drive serving for the multiplication, since only one of the two factors needs to be set up on the crank drive itself while the other factor may be transferred into the ratio. This latter circumstance again permits an easy skipping of the component values 0 and therewith avoidance of idle cycles.

Construction of the crank drive

The actual construction of the crank drive is shown in Figs. 8 and 9. The rod 24 consisting of two adjacent metal strips is linked to the crank 21. It has a rectangular cut out portion 24a in which can slide a guide piece 31 (Fig. 9). The guide piece 31 is loosely seated and rotatable upon the pivot pin 32. On the pin 32 there are further mounted the two loose guide pieces 33 adapted to slide in the guide bars 34 which are provided on both sides of rod 24 and are fast to the base plate. As a protection against mutual interference of rod 24 and the guide bars 34 and in order to prevent the guide pieces from sliding off, the disks 35 are provided between the guide pieces 31 and 33. The arrangement of the guide pieces permits sliding of the pin 32 in the guide bars 34, sliding of the rod 24 on the pin 32 and rocking of the rod 24 relative to the fixed guide bars 34 about the axis 32. The displacement of the guide pieces is effected by the two links 36 which are screwed fast to the pin 32. At the left hand end of the rod 24 the rocker 23 is connected by the link 26.

The positioning of links 36 and therewith of guide 25 is effected by crank 22 which in practice takes the form of a ratchet wheel. The rocker 37 connected to the links 36 is rotatably mounted at its right hand end on the stud 38 which is fast in the casing. The rocker 37 is necessary in order to safeguard the proper positioning of the link 36 and thereby also of the guide.

Movement of the ratchet wheel 22 is effected by pawl 39. The pawl 39 is rotatably mounted on the rocker 41 and is resiliently held against the ratchet wheel 22. The rocker 41 is driven by an eccentric 42 by the eccentric rod 43. The eccentric 42 is mounted upon the same shaft as the crank 21 so that the rocker 41 will rock back and forth once at each revolution of the crank 21. By this means the ratchet wheel 22 will be moved one step by means of pawl 39. By this movement the movement of the guide 25 is effected through rod 49 and the link 36, the rod 40 being pivotally mounted on the ratchet wheel 22.

The position of the guiding pieces in the guide bars 34 must be exactly defined after the rocker 23 has reached the outer dead centre. This is necessary since in this moment declutching of the storing and product device

wheel respectively takes place. As indicated above, this dead centre position also indicates the value for the associated position. During the remaining time the guide may be moved, this movement having however no influence upon the adjustment. The position of the guide has no influence upon clutching since the crank drive and the position of the guide bars 34 have been chosen in such manner that the position of the one dead centre is independent of the positioning of the guide.

Provision must be made that forces occurring and tending to move the guide from the predetermined position which must in no event occur at the outer dead centre, cannot have any influence. Therefore the ratchet wheel 22 is arrested at this moment and is blocked in both directions of rotation so that no unforeseen movements can arise. Blocking is effected by the lever 44 with its semicircular cut out portion 45. The cut out portion 45 of lever 44 can engage over the screw heads 46 thus blocking the rotation of the crank disk 22 in both directions. This blocking must be maintained for some time. Moreover, a quick engagement is desired which is obtained by a snap-action mechanism. The arm 47 is rotatably mounted upon the stud 48 fast to the casing and is connected through link 49 to the rocker arm 41. Therefore the arm 47 will rock synchronously with the rocker arm 41. Upon the stud 48 there is also rotatably mounted the lever 44 which is connected by spring 51 to the arm 47. Under the influence of the rocking movement of arm 47 the lever 44 will now continuously snap back and forth between the stop 52 and the screws 46. The dead centre has been positioned in such manner that the lever 44 engages the screw 46 when the guide or the screws 46 respectively have reached the proper position.

In order to compensate for tolerances and play and to permit an exact adjustment of the strokes the various screws 46 or the teeth 53 of the ratchet wheel are individually adjustable. The ratchet wheel 22 is constructed as a simple disk to which each of the teeth 53 is fastened by means of a screw 46. The screw holes in the disk are somewhat larger thereby providing a limited adjustability. In order to prevent rotation of the teeth 53 the latter engage inside with a disk. In order to compensate for differences in the division which possibly might occur by the assembling, a larger stroke has been provided for the pawl 39 than for the normal division.

The rocker 23 acts upon a set of gears (Figs. 8, 13 and 14) from which may be derived the various ratios in accordance with the values. In order to obtain a simple clutching operation and an axis for the drive which will be common to all ratios a planetary gearing is provided. The rocker 23 is constructed as a triangle and mounted on the shaft 54. Further the shaft 55 passes through a hole of the rocker 23 thereby providing a wider play in order to obtain a larger idle running and therewith a longer coupling period as has been already described above. In accordance with the rocking movement of the rocker 23 the shaft 55 will be taken with it, on which shaft are fast the gears 56, 57, 58 and 59. The shaft 55 is mounted in the sleeves 61 of the arms 62 and 63. These arms are fast on the shaft 54 which is mounted on the stud 64 of the shaft 65 and in the sleeve 66 of the stirrup 67. The stirrup 67 is fastened to the base plate and serves as a support for the gearing. The two arms 62 and 63 are, moreover, kept together by a pin 68.

The gears 56, 57, 58 and 59 are in engagement with the gears 69, 71, 72 and 73. The gear 69 is fast on the shaft 65 from which a drive for the accumulator setting is derived. The gears 71, 72 and 73 on the other hand are loosely mounted on the shaft 54. If one of the gears 71, 72 or 73 is arrested the associated gear 57, 58 or 59 of the reciprocating set of gears will roll upon the first one. Due to the different diameter with respect to gear 56 engaging the gear 69, the gear 69 and therewith the shaft 65 will receive a rotating movement in the sense opposite to that of the rocking movement of the set of

gears. Depending on the selection of the diameters of the gears the respective ratio will follow therefrom. The ratios of the diameters have been here so chosen that if the gear 71 is arrested a ratio of 1:1 results, upon arresting of the gear 72 a ratio 1:2 will result and upon arresting of the gear 73 a ratio 1:3.

Arresting of the gears is effected by the levers 74 and 75 (Fig. 8) which are mounted on the pin 77 and of which the noses 76 engage the teeth of the toothed wheels whereby arrest of said toothed wheels is effected. In this gearing always one of the three gears 71, 72 or 73 respectively must be arrested since otherwise a displacement of the gearing and therewith of the whole setting of the machine might occur. For this reason the lever 74 is permanently pressed by the spring 78 against the gear 71 by means of which a 1:1 relation is attained. A pin 79 is riveted to the lever 74, the pin 79 projecting past the two levers 75. If one of the levers 75 is rocked in clockwise direction it will encounter the pin 79 and take with it the lever 74. During this rocking movement the lever 75 reaches the teeth of the corresponding gear while the lever 74 is withdrawn from the teeth.

Rocking of the two levers 75 is effected by the magnets K¹ and K² the armature 81 of which is linked to the levers 75 with the bars 82. The levers 75 are held in their rest position by the springs 83, the rest position being determined by the stop 84. Moreover the armatures 81 act upon the contacts k¹ or k² respectively, the function of which will be referred to in the description of the wiring diagram below.

Consequently the ratio 1:1 is normally set up. If the magnet K¹ is energized the ratio 1:2 will be set up and by the magnet K² the ratio 1:3 is set up and the rocking of the crank drive is multiplied accordingly.

Clutch system for the storing device and product accumulator places

The construction of the clutch system for the storing device wheels and for the product accumulator wheels is the same so that it will be sufficient to describe the arrangement for the wheels of the storing device. The back and forth movement of the pinion 69 (Fig. 13) is transferred through a gear mechanism, which will be referred to later, to the shaft 91 having the gears 92 (Figs. 12 and 22) fast thereon. For each wheel of the storing device a pinion 45 is provided. The latter meshes with the pinion 93 which is firmly pressed upon the ring 94 (Fig. 23). In the ring 94 there is provided a slot 95 accommodating the pawl 96 and the spring 97. By spring 97 the pawl 96 may always be held in one of two rest positions. The ring 94 only rotates upon the teeth of the actuating wheel 98, which is mounted on the sleeve 99.

According to the value of the effective hole position each ring 94, driven by its pinion 92 will be rotated. If the clutch magnet has been energized slightly earlier by a hole in the card, the lever 101 will encounter the pawl 96, which will be pressed into the gap between the teeth of the actuating wheel 98, said pawl taking the wheel 98 with it in clockwise direction. Engagement of the pawl can only occur in a predetermined position, which is controlled by the cam contact it which is referred to latter on in the circuit diagram. The position of the pawl is determined during clutching by the crank drive as has already been mentioned. The movement of the actuating wheel 98 always takes place for a multiple of the pitch so that the teeth will always be again in the proper position for engagement.

Upon backward movement of ring 94 the actuating wheel 98 is locked against backward movement which is attained by spring 102 (Fig. 21). The spring 102 engages with a locking wheel 103 which is fast to the actuating wheel 98. The pawl 96 is forced outward by the inclined back face of the tooth until it reaches its outer position in which it will then be held by the spring 97. Accordingly, declutching will automatically take place

right at the beginning of the backward movement. The ring 94 will now run back until the dead centre for the next clutching operation is reached.

The actuation through the ring 94 from the drive 5 92 takes place in such a manner that the position of the actuating wheel 98 indicates the setting of the storing device.

Storing device for factors and product accumulator

The storing devices and the product accumulator are arranged at the rear side of the machine (Fig. 12). Their drive is effected by the gear 69 and the shaft 65, as has been already mentioned above. On the shaft 65 there is provided the worm wheel 100, which drives the worm wheel 105 of the shaft 106. On the shaft 106 there is also mounted the crank 107 (Fig. 18) to which the crank 109 is connected by means of the link 108. The crank 109 has the same length as the crank 107 and carries out the same rocking movements as the latter. With the link 108 there also engages the auxiliary crank 111 serving to avoid dead centres during the transfer. The crank 109 is rigidly connected to the gear 112 which meshes with the gear 113 on the shaft 91.

As already described above, the drive of the clutch 25 systems for the denominational elements of the storing device is effected from the shaft 91. The drive to the clutch systems of the denominational elements of the product accumulator is transferred through idle gears 104 (Fig. 12). The elements of the storing device are 30 mounted on the shaft 115, while the elements of the product accumulator—in the following always called accumulator elements—are mounted on the shaft 116. Each storing device comprises 8 elements and the accumulator comprises 16 elements. The setting of the storing and 35 accumulator elements is effected by similar clutch systems of which one has been already described above. The construction of the accumulator and of the storing device are similar to each other so that the operation of both may be explained in connection with Fig. 21 which only represents an accumulator element. The storing device 40 differs from the accumulator element only in that it has no tens transfer mechanism.

Clutching of the accumulator and storing device elements is effected by means of the levers 101 through 45 the magnets S or Z respectively, which are fast to the plate 117. The levers 107 are alternately arranged and mounted on the shaft 118. They are pressed against the plate 121 by means of the springs 119. If a magnet is energized it will press upon the lever 101 thereby clutching its accumulator or storing device element respectively. Setting of the storing elements is now effected from the crank drive value by value in accordance with the subsequent analysis of the individual hole positions.

The analysis of the storing devices for the multiplication 55 is effected again in component value combinations, as has been already described above. For this purpose each storing denomination has been furnished with four cam disks 122, 123, 124, and 125 (Figs. 24 to 27).

The positions of the cams on each of the various cam 60 disks have been chosen in such manner that the cams indicate again the component values of the accumulator setting. The cam disks are fast on the actuating gear 98 (Fig. 23) which represents the accumulator setting as already described. Further, the ratchet wheel 103 (Fig. 65 21) for locking against backward movement is fixed to the gear 98. The four cam disks are sufficient for the representation of the numerals since with the exception of the zero-position the numerical code extends only over four hole positions. The shapes and the relative positions of the cams with regard to each other is shown in Figs. 24-27. The cam disk 122 corresponds to the position I (Fig. 3) with component value 1, the cam disk 123 to the position II with component value 2, the cam disk 124 to the position III with component value 3 70 and the cam disk 125 to the position IV, also with com-

ponent value 3. With each cam disk is associated a contact spring 126 which can be pressed by the cams upon the common conductor 127. Depending upon the setting of the accumulator the four springs are brought into contact with the common conductor according to the code in Fig. 3. All springs 126 are fastened on the stirrup 128 by means of the plate. Two insulating places 129 (Fig. 21) insulate the springs from each other and from earth. The cam disks are separated from each other by the disks 149.

The analysis of the storing elements for the multiplicand is effected simultaneously for all denominations but consecutively for the various positions. The analysis of the storing elements for the multiplier however takes place successively for all positions of a denomination at the same time. This will be referred to in the description of the circuit diagram again later on. The various positions of all storing elements of the multiplicand are analyzed in compliance with the settings of the crank drive wherein one revolution of the crank 21 corresponds to the analysis of one position. According to the setting of the crank drive also, the analysis had been divided in six steps in which case four steps are provided for the analysis itself and two for the idle run.

If the storing device is to be analyzed the left hand shaft 131 (Fig. 12) is shifted step by step. The extent of the steps has been so chosen that the shaft 131 reaches its home position after six steps.

Each shaft 131 on which the cam disks 132 are mounted is of hexagonal section. For each spring 126 is provided a cam disk 132. The cams are offset relatively to each other by one sixth. The springs 126 are pressed by the cams one by one against the contact bars 133. A separate contact bar 133 is provided for each accumulator element, said bars being fastened to the insulating bar 134. The timing of the engagement of the springs with the contact bar corresponds to the analysis of the hole position on the card or to the settings of the crank drive respectively. However, current can only flow through the springs if the same are pressed at the same time against the common conductor 127 by the accumulator cams 122, 123, 124 and 125. The position of the cams 132 has been chosen in such manner that during the first four runs said cams press their springs 126 one by one against the common conductor 133.

When the multiplication is completed zeroizing of the storing devices will be effected so that new factors can be entered into the same. For this purpose a recess 135 is provided in the ratchet wheel 103 which is provided for each storing denomination, a spring 136 being situated in the recess. Upon setting of the storing devices this spring will slide through slots, which are provided in the sleeve 99. The sleeve 99 rotates during the setting of the storing devices in counterclockwise direction (Fig. 12) which, however, has no influence on the storing elements since the springs 136 may slide over the slots in the sleeve. If the storing devices are to be zeroized the sleeve will rotate once in clockwise direction. Depending upon the setting of the accumulator elements the springs 136 drop into the slots at different times so that the storing elements are taken with it by the sleeve and are zeroized.

The analysis of the storing devices or their multiples are transferred to the product accumulator and are added in the same. The determination as to whether the analysis itself of the storing devices, or a multiple thereof is to be transferred to the product accumulator will follow from the description later on. The sub-products are entered one by one into the accumulator elements and are added in the same. While there always is entered only a single number into the storing devices the accumulators receive one by one all sub-products. Accordingly, the accumulator wheel is completely rotated up to the final setting more than once on account of which a tens transfer is necessary.

The tens transfer mechanism is of a known construction similar to that of the Hollerith machines. The pawl 137 is rotatably mounted on the lever 138 and is pressed by spring 139 against the ratchet wheel 103. The lever 138 is rotatably mounted on the sleeve 99 and the spring 141 tries to rock the lever in clockwise direction. The lever 138 is however prevented from displacement by the nose 142 of lever 143. The lever 143 is pressed by spring 144 against the lug 145 of lever 138. When the accumulator wheel rotates, the pawl 137 will slide over the teeth of the ratchet wheel 103. To the pawl 137 a stud 146 is fastened which passes below the lever 143 of the next higher denominational accumulator place. The teeth as well as the stud 146 are formed in such a manner that the normal teeth will raise the stud 146 only so far that the latter cannot reach the lever 143. On the ratchet wheel there is provided adjacent to the normal teeth a larger tooth 147. Its position corresponds to the 9-position of the accumulator. If the tooth 147 passes the pawl 137 which means that the accumulator wheel has been moved from 9 to 0 the pawl 137 will be raised so far that the stud 146 engages the lever 143 of the next higher denominational accumulator place. The lever will release the lever 138 of its associated denominational place which latter lever will rotate under the tension of the spring 141 in clockwise direction until the lever engages the yoke 148. If at this time the pawl 137 engages the larger tooth 147 it will release, in the manner just described, the lever 143 for the next higher denominational place.

After the setting has been completed the yoke 148 will be rocked in counterclockwise direction and will restore to their home position the levers 138 which have been released. Hence the pawl 137 will move the ratchet wheel 103 for one unit thus completing the tens transfer. The analysis of the accumulator elements is effected for punching again in component value combinations, similar to the analysis of the storing elements for the multiplicand.

The storing devices and accumulators operate alternately in such manner that zeroizing takes place for the one while setting is effected for the other. The drive for zeroizing through the sleeves 99 and the tens transfer through the yoke 148 is derived from the crank 151 (Figs. 15 and 16). The latter has the same speed of rotation as the crank 21, namely it will rotate once per setting cycle. To the crank 151 is linked the rocker 152 through the link 153 and the rocker 154 through the link 155. The rocker 153 is fast upon the shaft 116, on which is also fast the yoke 148. Accordingly the yoke will reciprocate once per setting cycle.

The rocker 154 is mounted on the stud 156. On said rocker there is provided the pawl 157 which is rocked by the spring 158 in counterclockwise direction until the pin 159 on the pawl 157 engages the rocker. In normal position the pawl reciprocates without causing any effect. It is only if the magnet N is energized, and attracts its armature 161, that the same will move the gear 162 downwards (Fig. 16) by means of which the cams 163 on the gear 162 enter the range of the pawl 157. If now the pawl approaches the cams it will be raised by the inclined face of the cams and will subsequently drop between the two cams thus moving those and therewith also the gear 162 in the rocking movement. The rotation of the gear 162 is transferred to the two gears 164 and 165 which are provided on the two sleeves 99 for the zeroizing. In accordance with the direction of rotation of the gear 162 either the storing devices or the accumulators are zeroized. If the gear 162 rocks in clockwise direction (Fig. 15) the storing device will be zeroized, and if the gear 162 rotates in counterclockwise direction the accumulator is zeroized. The opposite rotation of the respective zeroizing sleeve 99 does not interfere with the setting since, as has been already described above, in this case the spring 136 is urged outwardly by the sleeve.

Upon rotation of the gear 162 the pin 166 temporarily opens the contact a^5 . Thereby the holding circuit is interrupted through the magnet N, so that the latter will drop and its armature will be restored to the home position by a spring. This, however, cannot take place immediately since it is prevented by the pin 166 which slides on the plate 168 (Figs. 16 and 17). It is only if the gear 162 has reached the final position that the pin 166 may slide off the plate and the gear 162 may be brought to the home position by the armature 161. Hereupon the cams 163 are moved out of the range of the pawl 157 so that the latter is now idly reciprocating again. The screws 169 serve as stops and to determine exactly the position as well as the rocking angle of the gear 162. This is required in order to obtain an exact zeroizing. If the magnet N is again energized the return movement of the gear 162 is effected. Upon a single energization of the magnet N the gear 162 will therefore move only in one direction. It is only upon the second energization of the magnet N that the gear will run back again. Consequently always the storing device or the accumulator is zeroized alternatively.

The analysis of the storing device of the multiplicand as well as the analysis of the product accumulator takes place step by step as has been already described above. Moreover the analyzing cycles take place also alternatively, similar to the zeroizing. The step by step shifting for the analysis of the storing device is derived from the rocker 152 which reciprocates once per setting cycle. To the latter the rocker 172 is linked by means of the link 171, the rocker being mounted on the stud 173. On the rocker 172 there are provided the two pawls 174 and 175 which are urged resiliently against the ratchet wheels 176 and 177. The pawl 174 acts here upon the ratchet wheel 176 on the shaft 131 for the analysis of the storing device and the pawl 175 acts upon the ratchet wheel 177 on the shaft 131 for the analysis of the accumulator.

Analyzing as well as zeroizing are effected oppositely to each other and alternately, i. e., if the storing device is zeroized the analysis of the accumulator will become effective and vice versa. Accordingly the setting of the analysis may be derived from the drive for the zeroizing. The position of the gear 162 indicates whether the storing devices or the accumulator have been zeroized so that this fact may be used for the control of the analysis. The gear 162 is connected to the eccentric disk 178. To the latter there is linked by means of the eccentric rod 179 the arm 181 which is mounted on the stud 182. Depending upon the position of the gear 162 or the eccentric disk 178 respectively the arm 181 is rocked upwards and downwards. Two pins 183 and 184 are provided on the arm against which pins the pawls 174 or 175 respectively are urged. If, however, the arm 181 is in the upper (illustrated) position thereby also the two pins have been moved upwards. In this instance the pawl 175 may now drop into the teeth of the ratchet wheel 177 and may shift the same step by step. On the other hand the pawl 174 is kept disengaged from the teeth by the pin 183 so that the pawl will push idly and no step by step shifting of the ratchet wheel 176 will be effected. If the arm 181 is in the lower position the pawl 174 will engage the ratchet wheel 176 while the pawl 175 will push idly. In this case the step by step analysis of the accumulator is effected. The safeguarding of the ratchet wheels and the locking against backward movement is effected by the detent springs 185.

In the accumulator there must be provided a device which suppresses the zero-punching before the highest significant figure of a number, but which permits punching of the zero within a number.

This is obtained by a particular wiring of contacts (Fig. 20). The wiring diagram in Fig. 20 shows only diagrammatically the wiring elements for the zero-suppression. Other wiring elements though included in this current circuit but serving other purposes have been

omitted and will be described later on in connection with the wiring. Each accumulator place has a set of contacts associated therewith generally indicated at z_0 . These consist of four contact springs of which the two lower ones (Fig. 21) are closed when unstressed. In the 0-position of the accumulator wheel the longer contact spring is pressed upwardly whereby the three upper springs establish a conducting connection between themselves and whereby contact with the lower spring is interrupted (Fig. 24). The actuation of these contacts is effected by the cams 186 on the intermediate disk 149. The location of the cam has been chosen in that way that the set of contacts z_0 is actuated when the accumulator wheel is at zero. If the accumulator wheel is moved from the 0-position the above mentioned shifting of the contacts will take place.

In Fig. 20 the Arabic index of the punch selector magnets L and of the contacts z_0 indicates with which accumulator denomination the same are associated. It has here been assumed that the units denomination is indicated by the Arabic index 1 and the higher denominations by the indices 2, 3, 4, 5. If it is for instance assumed that the number 3050 is to be analyzed from the accumulator, contact z_0^2 and z_0^4 will have been moved to the position shown in Fig. 20 since in the tens place (corresponding to z_0^2) and the thousands place (corresponding to z_0^4) the accumulator wheel has been moved. The zero-setting upon the selector magnets of the punch mechanism is effected through the contacts a^1_{II} , z_0^4 , z_0^3 to the selector magnet L^3 and through the contacts a^1_{II} , z_0^2 , z_0^1 to the selector magnets L^1 . Accordingly the wiring has been so arranged that when the V-position is positioned past the punching device, a current impulse will pass through the contact a^1_{II} and L^3 and L^1 will be energized whereby the punches associated with these magnets will be pressed through the card, thus causing zero-punching.

No current can flow through L^5 and the selector magnets of the higher places of the accumulator since the contact z_0^4 has interrupted the line in this direction. Nor can any current flow through L^4 and L^2 since the line to these magnets is interrupted at the contacts z_0^4 and z_0^2 (which have been shifted by their own accumulator place).

Moreover a device must be provided which permits all denominations of the multiplicand to be moved by one denomination in relation to the product accumulator after they have been multiplied by a denomination of the multiplier. This is obtained by a step by step selector (Fig. 8) which for reasons of space is divided into two separate selectors operating in parallel with each other. The distribution of the individual contact paths over the two selectors may be made arbitrarily.

The contact paths are comprised in the two contact fields 187, along which the two runners 188 may slide, the runners being driven by the step shift magnets D^1 and D^2 . If the step shift magnets are once energized the displacement of the runners for one step is effected. The runners comprise three arms for each path so that always one of them is in engagement with the contact path concerned and no idle run can arise. The runners are supplied with current by the lamellae 189 which are always in connection with the various arms of the runners. The current flow is effected through the remaining contact lamellae 191 to which the arms of the runners are shifted step by step.

The development of the plugging of the column shift operation device for the multiplicand is shown in Fig. 19. The first row to the left corresponds here to the lamellae 189 (Fig. 8) by means of which current supply is effected to the runners. The analyzing devices of the storing devices for the multiplicand are connected to said lamellae, which for reasons of simplicity are here designated at sk. The Arabic index indicates the denomination in the storing device. The number 1 corresponds

herein to the units denomination. To the lamellae 191 of the lowermost path and of the last row of all paths there are connected the accumulator clutch magnets Z the Arabic index of which also indicates the denomination. The lamellae are connected to one another as is indicated by the thick lines in Fig. 19. At the first step the analyzing device sk^1 acts upon the accumulator magnets Z^1 , the analyzing device sk^2 acts upon the accumulator magnet Z^2 and so on. At the second step the analyzing device sk^1 acts upon the accumulator magnet Z^2 and the analyzing device sk^2 acts upon the accumulator magnet Z^3 . Consequently displacement by one denomination is effected at the second step. At the next step again a displacement will take place and so on. During the step by step shifting there will also be a displacement from one denomination of the multiplier to the next one. In addition there are also provided further paths for the control of the multiplication which will be referred to later on in the description of the circuit diagram.

With the one selector with the magnet D^1 there are also associated the contacts d^1 and do for the control of the current path. The contact d^1 is constructed as a twin operating contact and is actuated by the armature of the magnet D^1 as soon as the same is attracted. The contact do is constructed as a shifting-rest-rest-contact the shifting contact being indicated at do_1 , the first contact at do_{11} , and the second rest contact at do_{111} . The control of the contacts is effected by the cams 192 which are rigidly connected to the runner 188 and rotate with the same. The position and the shape of the cams 192 has been so chosen that they actuate the contacts do at the moment when one of the arms of the runner is on the lamella 189 which corresponds to the starting position of the step by step selector.

Card feed

The cards are inserted into the magazine 193 (Fig. 10) and are fed by means of the card knives 194 to the rollers 195. The latter feed the cards past the analyzing brushes b in which case the entries are transferred to the storing devices. Subsequently the rollers feed the card to the punching device. The card is retained there up to the completion of the multiplication whereupon it is moved step by step past the punching device and punching of the product is effected. Subsequently the card is deposited in the magazine 196 on the carriage 197. The latter is guided in the pins 198 and is pressed upwardly by the spring 199. In its lowermost position the card carriage 197 opens the contact m (Fig. 18) whereby the entire current circuit through the machine is interrupted, thus stopping the machine.

The analyzing brushes b are fast in the insulating bar 201 and are supplied with current from the contact plate 202 which is fixed to the stirrup 203 by means of an insulating plate.

The step by step drive of the feed rollers and the drive of the card knife is effected by the crank 151 (Fig. 15), which—as has been already mentioned above—rotates once per setting cycle. To the crank 151 the rocker 204 is connected by means of the link 205. The rocker is rotatably mounted on the shaft 206. The pawl 208 is mounted on the rocker and is urged resiliently against the ratchet wheel 207 which is fast on the shaft 206. Consequently the shaft 206 is advanced for one step at each revolution of the crank 151. Backward movement of the ratchet wheel 207 is avoided by the detent spring 217. On the shaft 206 there are situated the worms (Fig. 12) which cause driving of the worm wheels 209 on the shafts 211, which latter also carry the feed rollers 195.

The ratio has been so chosen that the advancement of the ratchet wheel 207 for one pitch corresponds to the feed of the card for one position. The shaft 206 also drives a worm wheel which reciprocates the shaft 212 by means of a crank drive. The ratio has been so chosen that the shaft 212 reciprocates once per card cycle.

Upon the shaft there is provided the arm 213 which engages the slide 214, the latter being guided on the bars 215 and serving as a carrier for the card knives 194.

Above the ratchet wheel 207 (Fig. 15) there is provided a magnet T having an armature 216. If the armature has dropped it projects with one arm between the pawl 208 and the ratchet wheel 207 and accordingly prevents the pawl from dropping into the next tooth and thereby advancing the ratchet wheel. If the magnet T is energized it rocks its armature 216 in clockwise direction in which case the pawl can drop into the ratchet wheel, thus effecting the card feed. The armature 216 is kept on the contacts tr and tr_{11} in its rest position by spring 218. The contacts tr and tr_{11} are actuated as soon as the magnet T is energized. Their function will be referred to in the description of the circuit diagram later on.

Along the card path there are provided three card levers 219 (Fig. 11). Pins 221 thereon project through the side wall and actuate the contacts ka^1 , ka^{11} , ka^{111} , ka^2 , ka^{21} and ka^{211} . These serve to control the card run in dependence on the respective deck. Their effects will be referred to in the description of the circuit diagram later on. The Arabic index of the individual contacts indicates for which deck they will become operative, the Roman index indicates the sequence of the closure. The card levers 219 have been so constructed that they respond to the spaces between the cards. In addition there is provided a card lever 222 (Fig. 10). It detects whether there are still cards in the path or not. It actuates the contact k^4_1 the function of which will be referred to later on. It does not respond to the spaces between the cards.

35

Punching device

Punching is effected by means of the punches 223 (Fig. 10) which are guided in the bars 224 and 225 and are assembled with the matrix 226. By means of plates 227 this unit is fastened to the angle frame 228 (Fig. 11). The springs 229 keep the punches 223 in their upper position. The selection of the punches is effected by the magnets L, which are mounted on the bars 231 of the angle frame 228. Their armatures 232 act on the selector bars 233 which are guided in the combs 234. If a magnet is energized it moves its selector bar 233 to the left or to the right so that the full depth is passed beneath the punching yoke 235. The latter takes the selector bar with it downwards and presses the associated punch through the card. The punching yoke is fast to the two arms 236 which are mounted on the left hand guide comb 234 (Figs. 10 and 11) and which are linked to the two cranks 238 by means of the links 237. The cranks rotate once per setting cycle. Moreover a stirrup 239 is fastened to the two arms 236, the stirrup projecting past the spring 229. If now the arms 236 and therewith the punching yoke and the stirrup are moved upwards the stirrup 239 encounters the springs 229 and assists them in the withdrawal of the punches. The selector bars 223 and the armatures 232 are restored to their home position by the springs 241.

60

Drive

The machine is driven by the motor M which is connected to the worm shaft 242. The worm shaft 242 drives the worm wheel 243 on the shaft 244 on which latter is also provided the crank 21 for the crank drive. Moreover the worm shaft 242 drives the worm wheel 245 on the shaft 246 on which latter are provided the cranks 238 for the punching drive. The ratio of the two shafts 244 and 246 is the same, so that both operate at the same speed of rotation in such manner that they rotate once per operating cycle. The shaft 246 drives the shaft 248 at a 1:1 ratio through a pair of worm wheels 247, the crank 151 for the card feed and the accumulator control being mounted on the shaft 248.

75

In order to obtain a convenient and clearly arranged plugging of the machine wireless plugging has been chosen. The plug board is generally indicated at 249 and is located above the accumulator and the storing devices. With each plugging element, for inst. brushes, storing entries and so on, which are to be connected with one another, there are associated contact bars 251 (Fig. 31) which cross one another. Bars which cross one another are arranged in two layers which are insulated from one another. At each crossing point there is a hole in the contact bars whereby the connection between the two bars may be established by means of a plug 252. The division of the individual contact bars for the different switching elements is illustrated in Fig. 30. Within the range *b* are provided the contact bars for the brushes, within the range *S* are provided the contact bars for the storing entries. The selector magnets for the punches are connected within the range *L* and the accumulator outputs are connected within the range *zk*. Accordingly each brush may be connected with each storing entry and each accumulator output may be connected with each punching device. The selection is effected by insertion of the plugs into the respective crossing points.

Circuit diagram

In the illustration of the circuit diagram for the multiplying punch a simplified method has been chosen, as is generally used in the art of communication. If several identical units are provided, such as clutch magnets or brushes, only one of them is shown in the diagram while the remainder are indicated by the distribution connections only. The number of the units is indicated by the Arabic index number. The relays and magnets are indicated by capitals and the contacts which they actuate by the corresponding small letters. Manually actuated contacts are characterised by a key-like hook on the upper end of the movable contact member. Generally, the convention is such that the characters are situated to the right of the associated magnets, relays and contacts or above the wiring symbol respectively as far as they do not affect clarity. The contacts are shown in the positions which they occupy when the machine is at rest.

The wiring may be seen from the Figs. 28a, 28b which are associated. In order to facilitate reading of the circuit diagram the relay or cam diagram (Figs. 29a, 29b) is also shown. It indicates the responding or closing time of the relays and contacts, depending on the operating cycle of the machine. The operating cycle is one revolution of the crank 21 of the crank drive.

Six operating cycles of the crank 21 correspond to one full displacement of the crank drive through all sub-products including return to the starting position corresponding to one revolution of the disk 22. Every sixth operating cycle is separated from the next in the diagram by a thicker line. During the first four operating cycles the sub-product setting is effected while the last two cycles serve for the restoring of the crank drive. Six operating cycles are designated in the following description as one "setting cycle." Thus the latter corresponds to the subsequent multiplication of a component value of the multiplier by all component values of the multiplicand, in which accordingly the crank drive passes through all setting positions.

In the diagram it has been assumed by way of example that the number 8 is to be multiplied by the number 7. For an easier understanding of the time sequence of the operation of the machine the calculation is at first explained in connection with the diagram.

In the first setting cycle the number 8 is entered as multiplicand digit into a storing element (*s*) (Fig. 28a). Further it has been assumed that at the same time the number 6 is removed from an accumulator element and is transferred to the punching device (L). Subsequently

thereto zeroizing (N) of the accumulator and preparation of the machine for the next multiplication (D, H¹, H², H⁴) is effected during the last two operating cycles. The next three setting cycles show now the multiplication of the multiplicand 7 by the multiplier 8. In the first of these three setting cycles all component values of the numeral 8 (Z) are multiplied by the first component value of the numeral 7 (which is 1) (ratio 1:1 since neither K¹ or K² have responded). With the beginning of the 10 operation cycle "10" will be transferred to the next component value. K² has responded and since the second component value is zero, it will be skipped and immediately the third component value (which is 3) will be selected. In the following setting cycle therefore all component values of the numeral 8 (Z) are multiplied by the third component value of the numeral 7 (ratio 1:3). In the next setting cycle all component values of the numeral 8 are multiplied by the fourth component value of the numeral 7 (which is again 3) wherein also the ratio 1:3 is included (K²). At the moment "22" of this third setting cycle the multiplication of the numeral 7 by the numeral 8 is finished. Now, in the following operating cycles displacement to the multiplier denominations next in order, and the respective column shift operation of the multiplicand will be effected (D and H¹). If the multiplication is finished before the card has reached the punching device (T still in a state of response) shifting to the accumulator analyzing means and punching is prevented by the contacts of the magnet T until the card has reached the punching device, causing the de-energisation of the magnet T.

In connection with the wiring in Fig. 28 the operating cycles just described as well as the cooperation of the various electrical switching means are described more in detail. To this belong also the electrical shifting operations which are necessary for the operation of the machine in addition to the multiplication proper.

If the machine is switched on by means of the switch *e* the motor receives current through the two contacts *m* and *v*. Also current will flow through the contact *m*, through one of the contacts *ka¹₁*, *ka²₁*, or *ka³₁*, through the contact *dom*, through the heating coil of a thermo-contact, through a signal lamp, the contact *st_{III}*, through the feed magnet *T* to positive. The feed magnet *T*, however, does not respond since the current is reduced by the signal lamp and the heating coil of the thermo-contact. Flashing up of the signal lamp indicates to the operator that he is to press the key 257 (Fig. 2). Thereby he also actuates the contacts *st₁* to *st_{III}*.

The contact *st₁* is opened and interrupts the current circuit to the further switching elements of the machine. The two contacts *st_{II}* and *st_{III}* are shifted. By the shifting of the contact *st_{II}* the feed magnet receives the full current from the contact *dom* through the contact *st_{II}*, so that the latter can respond, by means of which the card feed proper becomes now operative. By shifting of the contact *st_{III}* the current circuit through the heating coil and the signal lamp has been interrupted, so that the signal lamp is extinguished.

The heating coil *V* is provided in order to avoid by error an exceedingly long idle run of the machine which is always indicated by flashing of the signal lamp. If current flows through the heating coil *V* for an exceedingly long time, the thermo-contact will respond, open and interrupt the current circuit through the motor. If then the key 257 is pressed, the current circuit through the heating coil will be interrupted by shifting of the contact *st_{III}*, so that the thermo-contact will cool down and close, and the machine will start running again.

The selection, through which of the three contacts *ka¹₁*, *ka²₁* or *ka³₁* the current is to flow, is made by plugging in one of the three plugging spots indicated by interrupted circles. If the connection to the contact *ka¹₁* is established, the machine is set to the upper deck, upon

connection to the contact ka^2 to the middle deck, and upon connection to the contact ka^3 to the lower deck. As has already been described above, the contacts ka are controlled by the three card levers 219 (Fig. 11).

In the following it will be assumed that the machine is set to the upper deck and that the connection to the card lever contact ka^1 is established by plugging. As has been already described above, the contact st_{II} has been shifted by depressing of the key, and therewith the current circuit through the magnet T has been established, so that the latter has responded and has rendered the card feed operative. Moreover the magnet T has actuated its magnets t_{II} and t_{III} . Hereby the contact t_{II} has been opened and the contact t_{III} has been closed. For the time being this has, however, not yet any influence on the machine.

Now, if the first card has reached the first card lever 219 the latter actuates the contacts ka^1_{II} and ka^1_{III} . The position of the card lever has been here so chosen that the first position of the first deck is slightly ahead of the analyzing brushes. The contact ka^1_{II} is therefore actuated by the card lever. By means of this the current circuit to the card feed magnet is interrupted through the contact do_{III} , so that the same becomes deenergised and the card feed is stopped.

By actuation of the card lever contact ka^1_{II} a current circuit is again established through the signal lamp, so that the same flashes up. Current flows from the card lever contact ka^1_{II} , through the depressed key contact st_{II} , through the signal lamp, through the heating coil of the delay contact, and actuated key contact st_{II} , through the magnet T to positive. Nevertheless the magnet T remains deenergised, since the current, being throttled by the signal lamp and the heating coil of the delay contact does not suffice to keep the magnet energized. Flashing of the signal lamp now indicates to the operator that he is to release the key 257 whereupon the contacts st return again to their home positions. Now, the current circuit through the signal lamp is interrupted by the two contacts st_{II} and st_{III} so that the lamp goes out.

During these operations the analyzing device serving for the sensing of the storing setting is operating, but has no influence on the machine since the two storing devices do not yet contain any setting. Even if this were the case, it would not have any adverse effect, since the storing devices are once more specially zeroized before the analysis proper of the card, as will be shown later.

By the rotation of the analyzing device for the storing means the two cam contacts a^3 and a^4 are actuated by the cams 253 and 254 (on shaft 131 for the analysis of the storing means, Fig. 18) in such manner that the actuation of the contacts a^4 is effected during the fourth operating cycle of the crank drive and of the contact a^3 during the first operating cycle. During the start of the fourth operating cycle the contact a^4_{II} is actuated. At the same time also the contact ir closes, which is instantaneously closed at each operating cycle. Now, current can flow from negative through the contacts m , st_{II} , the closed contact ka^1_{II} , the actuated contact a^4_{II} , the contact t_{II} , the cam contact ir , through a contact path of the step by step selector, through the relay H^1 to positive. The relay H^1 responds and actuates its contacts h^1_{II} to h^1_{III} .

Hereupon the contact h^1_{III} is closed, so that current flows through the cam contact a^4_{II} , which is still actuated, the contact t_{II} , through another contact path of the step by step selector, the contacts h^1_{III} and nr , through the reset magnet N. The latter responds and thereby zeroizes the storing devices. Also it actuates the two contacts nr and nr .

By means of the contact nr a holding circuit is established. Current flows from the card lever contact ka^1_{II} , through the two contacts a^5 and nr , through the reset magnet N. The contact nr is closed whereby the feed

magnet receives current through the contact st_{II} and responds, so that the card feed is rendered operative.

After zeroizing of the accumulator is finished the cam contact a^5 is temporarily opened, thereby interrupting the holding circuit through the magnet N so that the latter drops and its contacts nr and nr return to home position. Opening of the contact nr , however, has no influence on the feed magnet since the same is holding its own circuit over the contact t_{II} , the latter having been closed by said magnet. Now, current flows from the left plugging point through the card lever contact ka^1_{II} the contacts t_{II} and st_{II} , through the feed magnet to positive. The card is now shifted step by step.

By means of zeroizing of the storing devices the analyzing means of the storing devices have been disconnected and the analysis of the accumulator has been connected, as has been described already above. Therefore during the analysis of the accumulator actuation of the cam contacts a^1 and a^2 is effected by the cams 255 and 256 (upon the shaft 131 for the accumulator analysis, Fig. 18). The cam contacts a^2 close shortly before the first position of the card reaches the analyzing device. If now the first position is immediately under the analyzing device the cam contact ir is also closed instantaneously so that current may flow from positive through the contacts m , st_{II} , ka^1_{II} , ir , do_{II} , a^2_{II} , the closed card lever contact ka^1_{III} , through the brushes b and the plug board, through the clutch magnets of the storing devices S to positive. In accordance with the perforation in the card the clutch magnets S of the storing devices respond and energize the associated storing place.

Before shifting to the next position takes place the contact ir opens again. It closes as soon as the second position is under the analyzing device. By this means the perforation of the second position is transferred to the storing elements. When the fourth position (that is IV) is analyzed in addition to the contact ir also the cam contact a^2_{II} opens. Thus the purpose of the cam contact a^2_{II} is to close the current circuit to the brushes only as long as the deck is analyzed by said brushes. The purpose of the contact ir is to supply only a short current impulse to the magnet of the storing devices and to interrupt the current circuit before the brushes are lifted again from the card whereby sparking of the brushes is avoided.

During the first idle step the cam contacts a^1 are actuated instantaneously. The contact a^1_{II} is closed at this time so that as soon as the cam contact ir closes again current may flow from the latter through the contacts a^1_{II} , do_{II} , h^1_{II} , h^2_{II} , h^3_{II} , h^4_{II} , through the two step by step shifting magnets D^1 and D^2 to positive. The latter respond and shift the two step by step selectors for one step. Thereupon the runner arms of the lamellae 189 slide upon the first row of lamellae 191. At the same time the cam 192 slides off the contacts do so that the contact do shifts, the contacts do_{II} and do_{III} open.

By shifting of the contact do the two contacts a^1_{II} and ir are short circuited so that they no longer exercise any effect on the step by step shifting magnets. The contact do_{II} opens and interrupts the entire current circuit to the punch magnets and the magnets of the storing devices. The effect of the contact do_{III} will be referred to again later on.

By energizing of the magnet D^1 the twin contact d^1 is also closed. Therefore the relay H^1 receives current through the latter so that the same responds and actuates its contacts h^1 . The contact h^1_{II} opens by means of which the current circuit to the step by step shifting magnets D^1 and D^2 is interrupted and the same are deenergized.

Depending on the setting of the storing elements the contacts s have been closed. In the drawings the contacts s correspond with the springs 126 for the analysis. The Arabic index indicates herein the various storing

elements while the Roman index indicates the sequence of closure within a storing element. The storing elements have been so divided that the storing elements s^1 to s^8 receive the multiplicand and the storing elements s^9 to s^{16} the multiplier.

If now the ninth storing element which corresponds to the first storing element of the multiplier, is displaced, the contacts s^9 will have been closed accordingly. If it is assumed that this accumulator element is set to zero none of the contacts s^9_1 to s^9_{16} is closed. Consequently after opening of the contact d^1 the relay H^1 is again deenergized whereby also the contact h^1_{II} is closed and establishes the current circuit through the step by step shifting magnets D^1 and D^2 so that the same respond and advance the step by step selector for one step.

By closing of the contact d^1 the relay H^1 received again current so that the same responds, opens its contact h^1_{II} and in that way interrupts anew the current circuit through the step by step shifting magnets, so that the latter become deenergised. At this time the runner arm has been set to the second row of lamellae thus causing the relays H^1 to H^4 to be shifted to the next multiplier element which is indicated at s^{10} . If it is assumed that this element is set to number 7, the contacts s^{10}_1 , s^{10}_{III} , and s^{10}_{IV} are closed. Therefore upon closing of the contact d^1 not only the relay H^1 responds but also the relays H^3 and H^4 . The latter shift their contacts h^3_{II} and h^4_{II} by means of which also the current circuit to the step by step shifting magnets is interrupted. Also by means of the relays H^3 and H^4 their contacts h^3_1 and h^4_1 are closed which establish a holding circuit through the contacts a^4_{IV} and h^4_1 for the relay H^4 and a holding circuit through the contacts a^4_{III} and h^3_1 to the relay H^3 , so that these relays remain energized, even if the contact d^1 , conditioned by the deenergisation of the magnet D^1 , opens again.

Opening of the contact d^1 has also no influence on the relay H^1 since the latter receives current through the cam contact a^4_1 , the storing elements contact s^{10}_1 , through the contact path, and the closed contact h^1_1 .

At the beginning of the relay operations just described, which is to say during the fifth operating cycle, the contact a^1_{III} is also closed. If now the relay H^1 is energized for the first time it closes its contact h^1_{III} , thereby closing the current circuit to the reset magnet N . Current flows from the card lever contact ka^1_{II} through the cam contact a^1_{III} and the two contacts h^1_{III} and n_1 , through the reset magnet N to positive. The latter is energized and resetting for the accumulator is released. At the same time the contact n_1 is shifted by means of which the current circuit through the cam contact a^5 is established to which reference has been already made above. If zeroizing has been completed the holding circuit is interrupted by the cam contact a^5 so that the reset magnet drops again. In the meantime also the cam contact a^1_{III} is opened.

During the next four analyzing cycles now the contacts sk_1 to sk_{IV} of the eight storing elements for the multiplicand are closed one behind the other. Upon closing of the cam contact i_1 current may now flow from the same through the contacts s_1 , being closed depending on the position of the various storing element, through the contacts sk_1 , through the already described column shifting device, through the accumulator clutch magnets Z to positive. During the setting cycle the contact i_1 will open again. At the beginning of the next transferring cycle the contact i_1 is closed again and current flows now from the latter through the contacts s_{11} , closed in dependence on the setting of the storing elements, and the contact sk_{11} , now closed, through the column shifting device, through the accumulator clutch magnets Z to positive. This operation is now also repeated for the contacts sk_{111} and sk_{111} .

After the fourth operating cycle has been completed and when the first idle step takes place the cam con-

tacts a^4 are actuated instantaneously. The contact a^4 is shifted and the contacts a^4_{II} to a^4_{IV} are opened. The opening of the contacts a^4_{II} to a^4_{IV} has no influence on the machine since the same are short-circuited by the contacts k^1 , k^2 and the closed contact h^4_{IV} . By shifting of the contact a^4_1 the current circuit through the relay H^1 is interrupted so that the latter becomes deenergised. The contact h^4_{II} is closed so that now the clutch magnet K^2 receives current through the shifted contact do_1 , the contact h^4_{II} and the shifted contact h^3_{II} . The clutch magnet K^2 responds and clutches the gear 1:3 of the crank drive as has been already described above. Now again analyzing of the storing elements for the multiplicand will take place in the manner just described, with the only difference that now the setting of the accumulator element is effected with the triple value.

When the four operating cycles are finished the cam contacts a^4 are again actuated. Hereupon also the contact a^4_{III} opens so that in this instance the holding circuit to the relay H^3 is interrupted, for at this time also the contact k^2 is opened which is actuated by the clutch magnet K^2 . The relay H^3 is deenergized by means of which its contacts h^3_1 to h^3_{IV} return again to their home position. Opening of the contact h^3_{IV} has, however, no influence on the relay H^4 since in the meantime the cam contact a^4_{IV} has returned again to its home position. Also shifting of the contact h^3_{II} has no influence on the operation of the machine, since now the current is fed through the shifted contact h^4_{II} to the clutch magnet K^2 . Accordingly, a second setting cycle with the ratio 1:3 is now effected. When the setting cycle is again finished the cam contacts a^4 are actuated whereby the contact a^4_{IV} is opened and thus interrupts the holding circuit to the relay H^4 , since at this time also the contact h^3_{IV} is opened.

By deenergisation of the relay H^4 the contact h^4_{II} returns again to its home position thereby interrupting the current circuit through the clutch magnet K^2 and establishing the current circuit to the step by step shifting magnets D^1 and D^2 . The same respond and shift the selectors for one step, namely to the third row of lamellae. If now it is assumed that the third multiplier element is set to zero none of the contacts s^{11}_1 to s^{11}_{IV} is closed. Consequently upon closure of the contact d^1 only the relay H^1 will respond which interrupts by its contact h^1_{II} the current circuit through the step by step shifting magnets. The latter become deenergised and interrupt by their contact d^1 the current circuit to the relay H^1 which now becomes deenergised again. By closure of the contact h^1_{II} now the current circuit to the step by step shifting magnets is again established, which now respond again. This operating cycle is now repeated so long until a multiplier place is determined in which the setting is not zero.

It is now assumed that the numeral 5 is set in the next multiplier element. If now the selectors are shifted to this element, upon closure of the contact d^1 the two relays H^2 and H^3 receive current through the closed analyzing contacts s^{14}_{II} and s^{14}_{III} , so that the same respond and actuate their contacts h^2_1 to h^2_{III} , or h^3_1 to h^3_{III} respectively. By means of the contacts h^2_1 and h^3_1 , which are closed, the holding circuits for the relays are established. The two contacts h^2_{II} and h^3_{II} are shifted, which at this moment, however, has no effect, since the contact h^1_{II} is still opened. Further the two contacts h^2_{III} and h^3_{III} are closed and by this means a holding circuit for the relay H^1 is established. Due to the opening of the contact h^1_{II} and the shifting of the two contacts h^2_{II} and h^3_{II} the current has been interrupted by the step by step shifting magnets D^1 and D^2 , so that the same become deenergised. Opening of the contact d^1 has now, however, no longer any influence, since holding circuits have been established for the relays H^1 , H^2 , and H^3 .

At the beginning of the next setting cycle the cam contact a^3 is opened instantaneously thereby interrupting the

holding circuit to the relay H^1 and causing the latter to become deenergised. By this means the contact h^1_{II} , is closed so that now current flows through the shifted contact do_1 , through the contact h^1_{II} and the shifted contact h^2_{II} , through the clutch magnet K^1 . The latter responds and engages the ratio 1:2 on the crank drive. Now, upon the next setting cycle entering of twice the setting of the stored multiplicand is effected.

At the end of this setting cycle the cam contacts a^4 are then again actuated, whereby the contact a^4_{II} opens and interrupts the holding circuit to the relay H^2 , since at this time the contact k^1 is also opened which is actuated by the clutch magnet K^1 . Due to the deenergisation of the relay H^2 the contact h^2_{II} returns to the home position, thereby interrupting the current circuit to the clutch magnet K^1 and causing the same to become deenergised. Current flows now from the contact h^2_{II} through the shifted contact h^3_{II} to the clutch magnet K^2 , which responds and now engages the ratio 1:3 of the crank drive. The next setting cycle with the ratio 1:3 is now effected, on the occurrence of which three times the setting of the stored multiplicand is entered into the accumulator.

When this setting cycle is completed the cam contacts a^4 are again actuated whereupon the contact a^4_{III} opens and interrupts the holding circuit to the relay H^3 since at this time also the contact k^2 is opened. Due to the deenergisation of the relay H^3 the contact h^3_{II} returns again to its home position thereby re-establishing the current circuit to the step by step shifting magnets and causing the latter to respond. Now the advance of the selectors takes place in an alternating operation between the relay H^1 and the step by step shifting magnet D^1 and D^2 , as has been already described above.

This operation is continued until either a storing element is discovered which is not set to zero or until the step by step selector has again reached its home position. In this instance the contacts do are actuated whereby the contact do_1 shifts thereby causing interruption of the current circuit to the step by step shifting magnets.

When the multiplication by the last digit of the multiplier is finished, which need not necessarily be the last storing element the resetting of the storage devices must be effected so that the same are now free for entering of the next factors. The wiring has been so chosen, that it is not necessary to wait until the step by step selectors have been returned to the home position, but that the resetting is already initiated, when the last multiplier element is determined. For this reason a contact s_0 is provided for each multiplier element which contact is closed in the zero position of the storing element. The contacts are now so wired in series that they short-circuit one by one the various lamellae of one contact path, and only then if the accumulator element is set to zero. In accordance with the step by step shifting of the selectors also the switch arm is advanced through the contact path. However, current can never flow through this switch arm as long as the chain is interrupted by one of the contacts $s_0^1 \dots s_0^8$. It is only if the switch arm has been shifted over the last contact interrupting the chain that as soon as the cam contacts a^4 are actuated at the end of a setting cycle and the contact a^4_1 shifts current can flow from the contact a^4_1 , through the contact t_1 and the remaining contacts s_0 , through the contact path and the contact h^1_{III} which is closed at this time, to the reset magnet N , which establishes by means of the contact n_1 the holding circuit already described. This will initiate resetting for the storing devices as has been already described above.

In parallel with the multiplication operation the card is fed to the punching device so that it has reached the same before the multiplication is finished. When the card has reached the punching device the right hand card lever 219 (Fig. 11) and therewith the card lever contact k^1_1 return to the home position. Thereby the holding

circuit through the feed magnet T is interrupted so that the same disengages the card feed. Upon responding of the reset magnet N also the contact n_1 is closed whereby again the feed magnet T receives current and feeds the first deck of the card completely to the punching device. The card lever contacts ka^1 are actuated by the next following card and therewith the contact ka^1_1 is also shifted again and the holding circuit to the feed magnet T is established through the closed contact t_1 .

Until the first position of the first deck has reached the row of punches the step by step selectors have returned to their home position in the meantime, on the occurrence of which also the contact do_{III} has been closed by the cam 192. By means of this contact the clutch magnets S of the storing devices and the punch selector magnets L are now included in the current circuit. By resetting also the analysis of the storing devices has been mechanically disconnected and the analysis of the accumulators has been connected as has been already described above. Now in the next setting cycle entering of the factors of the next card into the storing device will take place, as has been already described above and simultaneously herewith the analysis of the accumulator places by means of the contacts $zk^1 \dots 16$ to $zk^4 1 \dots 16$ is effected which close consecutively in accordance with the position which is under the punching device. The contacts are herein always closed in accordance with the accumulator setting.

After the fourth position has been punched in the card and the fifth position is fed under the punching device the cam contact a^1_{III} closes instantaneously thereby supplying a current impulse through the contacts z_0 to the punch magnets L . The contacts z_0 are shifted in accordance with the resetting, as has been already described above, so that in the fifth position punching of the zero is effected, and that only within a number.

At the end of the setting cycle the resetting of the accumulator will then be initiated by the cam contact a^1_{III} and shifting to the storing device analyzing means is effected as has already been described above. The next multiplication cycles will now follow.

Now the possibility exists that the whole multiplication may be finished before the card has reached the punching device and the step by step selectors have reached their home position before the card has been stopped by one of the card levers 219 or their card lever contact ka^1_1 , ka^2_1 or ka^3_1 . In this instance the feed magnet T is still energized and therewith the contact t_1 is opened whereby initiation of the resetting through the cam contact a^4_1 and the contacts s_0 is avoided. Moreover through the contact t_1 also the current circuit through the contact h^1_1 to the relay H^1 is interrupted so that the same cannot respond. Resetting and therewith shifting for the analysis of the accumulator is consequently prevented until the contact t_1 is closed again, which is to say until the feed magnet has become deenergised or the card is ahead of the punching device. It is only if the cam contact a^4_1 is again shifted that the initiation of the storage resetting and the setting of the accumulator analysis can take place.

If an operating cycle of the machine is finished and if the last card is ahead of the punching device the card lever contacts ka^1 are the first ones which return to their home position. Hereupon the contact ka^1_1 interrupts the holding circuit to the feed magnet T , thereby stopping the card feed, as has been already described above. The contact ka^1_{II} opens; this has, however, no influence, since it is still short-circuited by the contact ka^3_{II} . The contact ka^1_{III} opens and interrupts thereby the current circuit to the brushes, so that now no transfer into the storage devices may be effected. If now the multiplication is finished and if the step by step selectors have again reached their home position initiation of the resetting and shifting to the accumulator analysis will take place. At

the same time also the card feed through the contact n_{11} is again switched on.

The holding circuit through the contact tr_1 is no longer established through the contact ka_{11} but through the cam contact a_{211} which is closed at the beginning of the resetting and which remains closed during the entire analysis or perforation respectively. If punching is finished the cam contact a_{211} opens and interrupts thereby the holding circuit through the feed magnet T. A current circuit will now be established through the card lever contact ka_{11} and the contact d_{111} closing after the multiplication, through the heating coil V, through the signal lamp and through the contact st_{11} through the relay T, so that the signal lamp will flash up and indicate that the machine is running idly. The operator has now to depress the key 257 whereby the contacts st are actuated.

Opening of the contact st_1 has herein no influence since it is short-circuited by the card lever contact ka^4 . The contact st_{11} is hereupon shifted so that the feed magnet will now receive current from the card lever contact ka_{11} through the contacts d_{111} and st_{11} . The magnet reponds and re-engages the card feed. By shifting of the contact st_{11} the current through the signal lamp is interrupted so that the same goes out. The last card is now fed to the receiving magazine. After it has been deposited there the card lever 222 and therewith the contact ka^4 return to the home position whereby the contact interrupts the entire controlling current circuit. If the last card has entered the magazine the operator may switch off the machine.

The whole current circuit through the machine may be interrupted by a contact m , which, as has been already described above, is opened as soon as the receiving magazine is filled with cards. In this instance the machine is stopped until the cards have been removed from the receiving magazine.

Key control

In Fig. 32 there is also illustrated diagrammatically a wiring diagram for a device which permits the factors to be entered into the machine manually. This would be for instance the case if enterings in a plurality of cards are to be multiplied by a constant factor. For this purpose a full keyboard would have to be provided for the machine, said keyboard being connected to an impulse emitter. In the wiring diagram (Fig. 32) the impulse emitter is represented by the cam disks 261 to 269. The cam shape of the individual cam disks is such that they conduct the sequence of impulses, consecutively to one line which is associated with the respective number according to the code (Fig. 3). The cam 261 consequently emits an impulse at the setting of the value 1, and thus corresponds to the numeral 1. The cam 262 emits an impulse at the setting of the value 2, and corresponds accordingly to the numeral 2. In this way a cam is provided for each numerical value. The cams rotate synchronously with the analysis of the storage devices. If now through the lines r^1 to r^8 one of the lines is connected to a certain impulse emitter by means of the contacts f actuated by the numerical keys, the respective sequence of impulses is supplied through the contact f in the machine to the associated accumulator element. The lines r^1 to r^8 correspond herein to the eight storing elements of the multiplier and the values are taken therefrom in the same way as values are taken therefrom by the multiplier storage device by means of the contacts s^9 to s^{16} , as has been already described above. In this instance the sequence of impulses is not derived from the storing elements but through the respective key contact f from the impulse emitter with the cams 261 to 269. The selection of the impulse sequence for the respective accumulator element is effected by the key contacts f . If for instance the third multiplier place is to represent the numeral 4, the impulse sequence is transferred from the cam 264 by the contact f^3_{11} to the conductor r^3 . 76

The conductor r^3 accordingly indicates the multiplier designation and cam 264 indicates the numeral.

What I claim is:

1. In a machine for multiplying two decimal digits, each of which is represented in the machine by retaining means according to a predetermined code in combinational component values the total of which amounts to the value of each respective digit, in combination, a unitary sub-product device adapted to multiply any two components in said retaining means by each other to form an individual sub-product, means for controlling said sub-product device for the successive individual multiplication of each component of the multiplier digit by all components of the multiplicand digit through said sub-product device by entering different components therewith, and sub-product accumulating means in which said sub-products are entered successively as they are formed.
2. In a machine as specified in claim 1 in which three or less component values are represented by said retaining means, multi-denominational sub-product accumulating means for entering said sub-products, all sub-products derived from said two decimal digits being entered in the accumulating element of the same denomination.
3. In a machine as specified in claim 1 in which component values are represented by said retaining means, the highest component product of which is 9 or less, sub-product accumulating means for entering said sub-products, all sub-products derived from said two decimal digits being entered in the accumulating element of the same denomination.
4. In a machine as specified in claim 1 in which the component values 1, 2, 3, 3 are represented by said retaining means, sub-product accumulating means for entering said sub-products, all sub-products derived from said two decimal digits being entered in the accumulating element of the same denomination.
5. A machine as specified in claim 1 wherein the unitary sub-product device includes a sub-product representing linkage common to all sub-product forming operations and cyclically controlled according to the sub-products as determined by the successive multiplication of said component values.
6. In a machine for multiplying a multi-denominational decimal multiplicand by a decimal multiplier digit, each digit of the multiplicand, and the multiplier digit, being represented in the machine by retaining means according to a predetermined code in combinational component values the total of which amounts to the value of each respective digit, in combination, a unitary sub-product device common to all denominations of the multiplicand represented in the retaining means and adapted to multiply like component values of each of the multiplicand denominations by a component value of said multiplier digit to form an individual sub-product of each multiplicand denomination, means for controlling said sub-product device for the successive individual multiplications of each component value of the multiplier digit by all component values of the multi-denominational multiplicand digits through said sub-product device by entering different components therewith, and multi-denominational sub-product accumulating means in which said sub-products are entered successively as they are formed.
7. A machine as specified in claim 6 wherein the unitary sub-product device includes a sub-product representing linkage common to all denominations of the multiplicand retaining means and being common to all sub-product forming operations, and means for cyclically controlling said linkage according to the sub-products as determined by the successive multiplication of said component values.
8. In a machine for multiplying a multi-denominational decimal multiplicand by a decimal multiplier digit, each digit of the multiplicand, and the multiplier digit, being represented in the machine by retaining means

according to a predetermined code in combinational component values the total of which amounts to the value of each respective digit, in combination, a unitary sub-product device common to all denominations of the multiplicand represented in the retaining means and adapted to multiply like component values of each of the multiplicand denominations by a component value of said multiplier digit to form an individual sub-product of each multiplicand denomination, means for controlling said sub-product device for the successive individual multiplications of each component value of the multiplier digit by all component values of the multi-denominational multiplicand digits through said sub-product device by entering different components thereinto, and multi-denominational sub-product accumulating means in which said sub-products are entered successively as they are formed, said sub-product device consisting of drive mechanism coupled to said accumulating means, and said means for controlling the sub-product device including mechanism connected to the drive mechanism for varying the effective motion transmitted thereby to the accumulating means.

9. In a machine for multiplying a multi-denominational decimal multiplicand by a decimal multiplier digit, each digit of the multiplicand, and the multiplier digit, being represented in the machine by retaining means according to a predetermined code in combinational component values the total of which amounts to the value of each respective digit, in combination, a unitary sub-product device common to all denominations of the multiplicand represented in the retaining means and adapted to multiply like component values of each of the multiplicand denominations by a component value of said multiplier digit to form an individual sub-product of each multiplicand denomination, means for controlling said sub-product device for the successive individual multiplications of each component value of the multiplier digit by all component values of the multi-denominational multiplicand digits through said sub-product device by entering different components thereinto, and multi-denominational sub-product accumulating means in which said sub-products are entered successively as they are formed, said sub-product device consisting of drive mechanism coupled to said accumulator means and including a link rockable about a pivot point and said means for controlling the sub-product device including mechanism for shifting said pivot point.

10. The machine as defined in and by claim 8 wherein the effective motion transmitted by said drive mechanism is altered by the mechanism connected thereto in accordance with the various component values of said multiplier.

11. In a machine for multiplying two decimal digits, each of which is represented in the machine by retaining means according to a predetermined code in combinational component values the total of which amounts to the value of each respective digit, in combination, a unitary sub-product device adapted to multiply any two components in said retaining means by each other to form an individual sub-product, means for controlling said sub-product device for the successive individual multiplication of each component of the multiplier digit by all components of the multiplicand digit through said sub-product device by entering different components thereto, and sub-product accumulating means in which said sub-products are entered successively as they are formed, said sub-product device consisting of drive mechanism coupled to said accumulating means, said drive mechanism including a rocking link connected to a rotating crank, said means for controlling the sub-product device including mechanism for shifting the radial point of connection between said crank and said link and mechanism for shifting the rocking point of said link to vary the effective motion transmitted by said drive mechanism to said accumulating means.

12. In a machine for multiplying two decimal digits, each of which is represented in the machine by retaining means according to a predetermined code in combinational component values the total of which amounts to the value of each respective digit, in combination, a unitary sub-product device adapted to multiply any two components in said retaining means by each other to form an individual sub-product, means for controlling said sub-product device for the successive individual multiplication of each component of the multiplier digit by all components of the multiplicand digit through said sub-product device by entering different components thereto, and sub-product accumulating means in which said sub-products are entered successively as they are formed, said sub-product device consisting of drive mechanism coupled to said accumulating means and including a pair of rockable links, and said means for controlling the sub-product device including mechanism for shifting the rocking points of said links to vary the effective motion transmitted by the drive mechanism to said accumulating means.

13. In a machine for multiplying two decimal digits, each of which is represented in the machine by retaining means according to a predetermined code in combinational component values the total of which amounts to the value of each respective digit, in combination, a unitary sub-product device adapted to multiply any two components in said retaining means by each other to form an individual sub-product, means for controlling said sub-product device for the successive individual multiplication of each component of the multiplier digit by all components of the multiplicand digit through said sub-product device by entering different components thereto, and sub-product accumulating means in which said sub-products are entered successively as they are formed, said sub-product device consisting of drive mechanism coupled to said accumulating means through one of a plurality of power paths, each having a different effective drive ratio, said drive mechanism including a rockable link, and said means for controlling the sub-product device including mechanism for selecting one of said paths of power and mechanism for shifting the rocking point of said link so as to vary the effective motion transmitted by said drive mechanism to the accumulating means.

14. In a machine for multiplying a multi-denominational decimal multiplicand by a decimal multiplier digit, each digit of the multiplicand, and the multiplier digit, being represented in the machine by retaining means according to a predetermined code in combinational component values the total of which amounts to the value of each respective digit, in combination, a unitary sub-product device common to all denominations of the multiplicand represented in the retaining means and adapted to multiply like component values of each of the multiplicand denominations by a component value of said multiplier digit to form an individual sub-product of each multiplicand denomination, means for controlling said sub-product device for the successive individual multiplications of each component value of the multiplier digit by all component values of the multi-denominational multiplicand digits through said sub-product device by entering different components thereto, and multi-denominational sub-product accumulating means in which said sub-products are entered successively as they are formed, said sub-product device consisting of drive mechanism coupled to said accumulating means through one of a plurality of power paths, each having a different effective drive ratio, said drive mechanism including a rockable link, and said means for controlling the sub-product device including mechanism for selecting one of said paths of power and mechanism for shifting the rocking point of said link so as to vary the effective motion transmitted by said drive mechanism to the accumulating means.

15. The machine as defined in and by claim 14 wherein said sub-product device is controlled cyclically in accordance with the different like component values in the various denominations in the multiplicand, and individually in accordance with the different component values of the multiplier.

16. The machine as defined in and by claim 15 wherein the paths of power in said drive mechanism are selected in accordance with the component values of said multiplier.

17. In a machine for multiplying a multi-denominational decimal multiplicand by a decimal multiplier digit, each digit of the multiplicand, and the multiplier digit, being represented in the machine by retaining means according to a predetermined code in combinational component values the total of which amounts to the value of each respective digit, in combination, a unitary sub-product device common to all denominations of the multiplicand represented in the retaining means and adapted to multiply like component values of each of the multiplicand denominations by a component value of said multiplier digit to form an individual sub-product of each multiplicand denomination, means for controlling said sub-product device for the successive individual multiplications of each component value of the multiplier digit by all component values of the multi-denominational multiplicand digits through said sub-product device by entering different components thereinto, and multi-denominational sub-product accumulating means in which said sub-products are entered successively as they are formed, said means for controlling the sub-product device including mechanism for automatically advancing the multiplication to the next sub-product step when a component value of the multiplier constitutes 0.

1. In a machine for multiplying a multi-denominational decimal multiplicand by a multi-denominational decimal multiplier, each digit of the multiplicand and of the multiplier being represented in the machine by retaining means according to a predetermined code in combinational component values the total of which amounts to the value of each respective digit, in combination, a unitary sub-product device common to all denominations of the multiplicand represented in the retaining means and adapted to multiply like component values of the multiplicand denominations by a component value of said multiplier digit to form an individual sub-product of each multiplicand denomination, means for controlling said sub-product device for the successive individual multiplications of each component value of the multiplier digit by all component values of the multiplicand digits through said sub-product device by entering different component values thereinto, the latter being also common to all sub-product forming operations, multi-denominational sub-product accumulating means in which said sub-products are entered successively as they are formed, and means for automatically changing the denominational operative relation of said accumulating means with respect to the means for entering the sub-products in said accumulating means after each component value of a denomination of the multiplier retaining means has been multiplied by each component value of the multiplicand retaining means.

19. In a machine for multiplying two decimal digits, each of which is represented in a record by hole combina-

tions according to a predetermined code in which the holes represent component values, the total of which amounts to the value of each respective digit, in combination, means for analyzing said component value representing holes, a unitary sub-product device adapted to multiply any two component values by each other to form an individual sub-product, means for controlling said sub-product device for the successive individual multiplication of each component value of the multiplier digit by

10 all component values of the multiplicand digit through said sub-product device by entering different component values thereinto, and sub-product accumulating means in which said sub-products are entered successively as they are formed.

20. In a machine for multiplying two decimal digits, each of which is represented in a record by hole combinations according to a predetermined code in which the holes represent component values, the total of which amounts to the value of each respective digit, in combination, means for analyzing said component value representing holes, a unitary sub-product device adapted to multiply any two component values by each other to form an individual sub-product, means for controlling said sub-product device for the successive individual multiplication of each component value of the multiplier digit by

25 all component values of the multiplicand digit through said sub-product device by entering different component values thereinto, and sub-product accumulating means in which said sub-products are entered successively as they are formed, said sub-product device being also adapted to consecutively enter the component values of the hole combinations into retaining means.

21. In a machine for multiplying two decimal digits, each of which is represented in a record by hole combinations according to a predetermined code in which the holes represent component values, the total of which amounts to the value of each respective digit, in combination, means for analyzing said component value representing holes, a unitary sub-product device adapted to multiply any two component values by each other to form an individual sub-product, means for controlling said sub-product device for the successive individual multiplication of each component value of the multiplier digit by

35 all component values of the multiplicand digit through said sub-product device by entering different component values thereinto, and sub-product accumulating means in which said sub-products are entered successively as they are formed, said analyzing means being directly operatively connected with said sub-product device for forming a sub-product in accordance with the holes analyzed.
